ABSTRACT OF THE DISCLOSURE

A circuit is provided to stabilize beam current in a vidicon camera tube. A vidicon tube has an electron emitting cathode, a control electrode, and a light responsive signal electrode. Conventional means collect most of the electrons emitted by said cathode and focus a relatively small portion of the electrons emitted by the cathode into a beam. Conventional means cause the beam to scan the signal electrode to produce a picture signal related to the distribution of light on the signal electrode. The stabilizing circuit comprises a resistor of large resistance connected between the cathode and a source of fixed reference potential. The control electrode is preferably grounded. The electron current from the cathode produces a voltage across the resistor which adds to the reference potential to bias the cathode relative to the control electrode to produce electron current to the signal electrode of suitable intensity, the resistance of the resistor being so large that the resistor responds to changes in the electron current from the cathode by producing a corresponding change in bias on the cathode sufficient to maintain the average flow of electrons from the cathode substantially constant. Positive blanking pulses are applied to the cathode to cut off the flow of electrons during the pulses.

This invention relates to television cameras and more particularly to the control of beam current striking the signal electrode of a vidicon tube. Still more particularly, the invention relates to establishing an electron beam of suitable intensity in a vidicon tube and to stabilizing this beam intensity with aging of the tube.

Television cameras commonly include a vidicon tube having an electron emitting cathode, a control electrode, various focusing electrodes and a light-responsive signal electrode. In cameras using vidicon tubes, electrons are emitted from the cathode at a rate dependent upon the relative potential of the adjacent control electrode, as well as upon the temperature and emission qualities of the cathode. By means of the focusing electrodes, in association with a focusing magnetic field, certain of the emitted electrons are formed into a relatively sharp beam directed toward the signal electrode. Horizontal and vertical deflection coils adjacent the tube deflect the electron beam to cause it to scan the signal electrode. In the course of the scanning, the electrons in the beam discharge the charge formed on the signal electrode by the action of incident light and thereupon produce an output signal related to the distribution of the incident light upon the signal electrode. This output signal is then processed into a composite picture signal which may be utilized for transmission of a television signal or for operation of a video recorder or monitor.

In order to develop a proper output signal, it is necessary to scan the signal electrode with a beam of suitable intensity to deposit the desired charge upon the signal electrode. The beam current, being dependent upon the difference in voltage between the cathode and the control electrode, can be controlled by this difference. The control electrode must be biased negatively relative to the

cathode in order to establish the desired current. To this end, it is conventional to ground the cathode and to apply a negative bias potential to the control electrode.

In the scanning operation in television cameras, the beam is deflected from one side to the other and from top to bottom, and it is necessary to blank the beam current, that is, to turn it off, during the retrace of the scanning operation, otherwise the retrace will appear on the reproduced picture. Blanking pulses derived from the deflection circuits are used for this purpose. Often, a resistor is inserted between the cathode and ground, and positive pulses are applied to the cathode to turn off the beam current during the retrace.

As vidicon tubes age, the cathode electron emissivity ordinarily decreases, thus requiring lower bias to achieve the desired beam current. To achieve this lower bias, the negative power supply coupled to the control electrode is ordinarily made variable so that adjustments can be made from time to time during the life of the tube.

According to the present invention, the negative power supply and its control are both eliminated. Instead, a relatively large cathode resistor is used to develop the required bias. The resistor may be returned to a positive potential. There is then no need for any negative power supply, and the control electrode can be grounded, thus omitting a number of costly parts.

Vidicon tubes are inherently inefficient. Most of the electrons emitted from the cathode travel to the focusing electrodes without ever reaching the signal electrode as part of the directed beam. Ordinarily, this merely represents wasted current and power without serving a useful purpose. The present invention, however, takes advantage of the fact that the signal electrode current is negligible in magnitude relative to the magnitude of the current flowing to the focusing electrodes. It permits a relatively large cathode resistor to be introduced without any substantial degeneration of the signal. That is, the total electron emission current is so large relative to the signal electrode current that variations in the signal electrode current have substantially no effect upon the cathode potential. At the same time, the relatively large current flowing to the focusing electrodes has a material effect upon the cathode potential.

As the emissivity of the cathode begins to drop off with the aging of the tube, the current to the focusing electrodes decreases. The flow of current through the cathode resistor therefore decreases. The voltage across the cathode resistor therefore decreases, thus reducing the potential of the cathode relative to the control electrode. This represents a decrease in bias which in turn tends to increase the flow of electrons from the cathode to balance the decrease occasioned by loss of emissivity, hence stabilizing the cathode current.

It is therefore a primary object of the present invention to control the beam current in a vidicon tube. It is a further object of the present invention to stabilize the beam current in a vidicon tube upon the aging of the tube. It is still a further object of the invention to control beam current without the need for negative power supplies. Another object of the invention is to control beam current in a vidicon tube operated with its control electrode grounded and without the need for a negative power supply.

Further objects and advantages of the present invention will become apparent from consideration of the following description, particularly when taken in connection with the appended drawing in which:

The single figure is a diagrammatic illustration of a preferred form of the beam control apparatus of the present invention.

The drawing illustrates a television camera circuit and in particular one including a vidicon tube 10. The vidicon

tube includes a cathode 12 indirectly heated by a filament 14, the filament 14 being connected by a filament power supply 16 which supplies the power to heat the filament. The tube further contains a control electrode 18 and some sort of focusing electrode means illustrated generally as focusing electrodes 20 and 22. In some vidicon tubes, there may be additional focusing electrodes. Vidicon tubes generally include as focusing electrodes a plurality of cylindrical electrodes having suitable apertures for defining and focusing an electron beam. The tube further includes a signal electrode 24. Associated with the vidicon tube 10 are horizontal and vertical deflecting coils 26 and a focusing coil 28.

In accordance with the preferred embodiment of the present invention, the control electrode 18 is directly connected to ground. The cathode 12 is connected to one end of a resistor 30 the other end of which is connected to the positive side of a low voltage regulated power supply 32. A high voltage regulated power supply 34 supplies positive potential through a load resistor 36 to the signal electrode 24. The focusing electrode 20 may be connected to the same terminal of the power supply 34. Further, this power supply 34 may supply positive potential to focusing coil 22 through a voltage divider 37 comprising resistors 38 and 39.

The operation of the vidicon tube may be explained as follows: The heated filament 14 heats the cathode 12 causing it to emit electrons. The emitted electrons are attracted to the focusing electrodes 20 and 22 and to the signal electrode 24 because of the high positive potential applied to these electrodes. A more positive potential is applied to these electrodes than appears on the cathode 12. The magnitude of this electron current is limited, however, by the relative potential of the control electrode 18. The control electrode 18 is at a potential negative with respect to the potential of the cathode 12 and therefore inhibits the free flow of electrons.

Electrons from the cathode that pass the control electrode 18 are defined into a narrow beam by the conjoint operation of the focusing electrodes 20 and 22 and the focusing coil 28. The focusing coil 28 is energized by means not shown to provide an axial magnetic field for magnetic focusing of the moving electrons. The focusing electrodes 20 and 22 provide electrostatic focusing which operates in conjunction with the magnetic focusing to produce a relatively narrow beam of electrons. The horizontal and vertical deflecting coils 26 supply additional magnetic fields which cause the electron beam to be deflected magnetically, causing the beam to scan the surface of the signal electrode 24 in accordance with the conventional television scanning scheme. The fields produced by the horizontal and vertical deflecting coils are controlled by respective signals from a horizontal deflection circuit 40 and a vertical deflection circuit 42.

The signal electrode 24 is photosensitive. The action of the light upon the signal electrode builds up a charge pattern upon the electrode. It is the discharge of this charge pattern by the electron beam that produces the flow of current through the load resistor 36 thereby developing an output signal at the signal electrode 24. This signal is applied through a coupling capacitor 44 to an amplifier 46 which may, as shown, comprise a number of stages of amplification. The output of this amplifier, with appropriate signal processing to include synchronizing pulses, becomes the composite picture signal which may be used to modulate a carrier signal for television transmission or may be used to operate a monitor or a video recorder.

The horizontal and vertical deflection circuits 40, 42 develop signals which may be used for developing appropriate blanking and synchronizing pulses. These signals are applied to a blanking pulse circuit 48 to develop horizontal and vertical blanking pulses. These blanking pulses are applied through a coupling capacitor 49 to the cathode 12 to stop electron emission during the time of the retracing of the electron beam after each horizontal and vertical

sweep. This is necessary to avoid destroying any of the charge on the signal electrode during retrace which would adversely affect the reproduced picture. At the same time the blanking pulses are applied to one of the stages of the amplifier 46 to form the blanking pulses in the composite picture signal.

The signals from the deflection circuits 40, 42 are also applied to a synchronizing pulse circuit 50 to develop horizontal and vertical synchronizing pulses. These pulses are applied to a succeeding stage of the amplifier 46 to form the horizontal and vertical synchronizing pulses in the composite picture signal.

A vidicon tube typically operates with the electrode 20 at about 300 volts positive and the electrode 22 at a slightly lower positive voltage. With about 300 volts positive applied to the load resistor 36, the signal electrode 24 operates in the range of 50 volts positive, when beam current is flowing to the signal electrode 24. Typical bias between the cathode 12 and the control electrode 18 is about 40 volts.

In accordance with the present invention, this cathode to control electrode bias is achieved by the conjoint operation of the power supply 32 and cathode current flowing through the resistor 30. Typically, the power supply 25 32 is a regulated power supply developing about 18 volts positive. Typical cathode emission current is about 500 microamperes, most of which is collected by the focusing electrodes 20 and 22. The portion of the current in the electron beam that strikes the signal electrode is typically 30 less than one-tenth of one percent of the total cathode current. With a cathode current of 500 microamperes, a cathode resistor 30 of 47,000 ohms resistance develops a voltage thereacross of 23.5 volts, thus making the bias between the cathode 12 and the control grid 18 about 41.5 volts.

The blanking pulses are formed in a blanking pulse circuit 48 and applied through a capacitor 49 to the cathode 12. These blanking pulses are typically 18 volts positive and serve to cut off the cathode current for the duration of the pulse. The resistor 30 isolates these pulses from 40 ground.

The various vidicon tubes differ in their characteristics. It is therefore often desirable that the resistance of the resistor 30 be determined empirically. To so determine the proper resistance, the vidicon tube may be placed in operation and the resultant picture observed upon a monitor. Since the beam current striking the signal electrode determines the highlights in the monitored picture, the resistor 30 may then be adjusted to establish the beam current giving a suitable picture. Adjustment of the resistor 45 50 55 30 adjusts the cathode to control electrode bias which controls the total electron emission from the cathode and hence that part which forms the electron beam. The resistor 30 may therefore be adjusted to that resistance which produces proper discharge of picture highlights. Once the proper resistance is established, a fixed resistor 55 may be used as resistor 30.

The use of cathode resistors to develop cathode to control electrode bias is, of course, old; however, when cathode resistors are used to develop such bias, they are bypassed by a capacitor in order not to degenerate the signal. That is, when the signal current flows through the cathode resistor, it ordinarily creates a bias which develops an opposing signal degenerating the signal voltage. In the present circuit it is undesirable to bypass the resistor 30 with a capacitor, for it is desired to apply blanking pulses to the cathode, and a bypassing capacitor would bypass the blanking pulses.

The present invention not only operates without bypassing the resistor, but takes advantage of the great inefficiency of the vidicon tube to develop the desired bias without being degenerative in respect to the signal. As noted earlier, the signal electrode current is typically less than one-tenth of one percent of the total cathode current. Most of the cathode current is wasted in being collected 70 75 by the focusing electrodes 20 and 22. Because of this

waste, however, the cathode current can be used to develop the cathode to control electrode bias without degeneration of the signal. That is, the very large cathode current can be stabilized at about 500 microamperes without any substantial effect upon the signal current portion.

If the cathode current decreases, as for example because of aging of the tube, the voltage developed across the resistor 30 decreases correspondingly. This reduces the cathode to control grid bias, thus increasing the electron flow and tending to restore the cathode current. At the same time the signal current portion varies over only a few tenths of a microampere. Such variations have a negligible effect upon the voltage developed across the resistor 30. Thus, although the circuit is highly degenerative in respect to the total electron current and the focusing electrode current, it is not degenerative in respect to the signal current.

Although a preferred embodiment has been described in some detail, various modifications thereof can be made without departing from the scope of this invention. For example, under some circumstances the low voltage power supply 32 can be eliminated and the resistor 30 connected directly to ground; under these circumstances the entire cathode to control grid bias can be developed by the cathode current flowing through the resistor 30.

Other modifications are also within the scope of the invention as claimed.

I claim:

1. In a vidicon camera including a vidicon tube having an electron emitting cathode, a control electrode, and a light responsive signal electrode, means for collecting most of the electrons emitted by said cathode and focusing a relatively small portion of the electrons emitted by said cathode into a beam, means for scanning said signal electrode with said beam to produce an output signal related to the distribution of light on said signal electrode,

and means for applying positive blanking pulses to said cathode to cut off the flow of electrons during said pulses: circuit means connected to said cathode for stabilizing the emission of electrons from said cathode, said circuit means comprising a resistor of large resistance connected between said cathode and a source of first fixed reference potential, means for connecting said control electrode to a source of second fixed reference potential, the electron current from said cathode producing a voltage across said resistor which adds to said first reference potential to bias said cathode relative to said control electrode to produce electron current to said signal electrode of suitable intensity, the resistance of said resistor being a substantial fraction of the effective resistance traversed by said electron current so that said resistor responds to changes in said electron current from said cathode by producing a corresponding change in bias on said cathode sufficient to maintain the average flow of electrons from said cathode substantially constant.

2. A circuit according to claim 1 wherein said second reference potential is ground and said first reference potential is at least as positive as ground.

3. A circuit according to claim 1 wherein said resistor is unbypassed.

4. A circuit according to claim 1 wherein said first and second reference potentials are substantially the same.
